[75] Inventor: **Heinrich Lang**, Seenheimer Strasse Lola, D-91465 Egesheim, Germany*Primary Examiner*—Louis S. Zarfas*Assistant Examiner*—Frank Martinez*Attorney, Agent, or Firm*—Dority & Manning**[73] Assignees:** **Heinrich Lang**, Ergersheim, Germany; **Sabine Lang**, Chapin, S.C.**[57] CLAIM****[**] Term:** **14 Years**

The ornamental design for rear-view mirror and antenna assembly, as shown and described.

[21] Appl. No.: **52,055****DESCRIPTION****[22] Filed:** **Mar. 22, 1996****[51] LOC (6) Cl.** **12-16****[52] U.S. Cl.** **D12/188****[58] Field of Search** **D12/187, 188; 359/844, 850, 863, 889, 864, 865, 866**

FIG. 1 is a top front perspective view thereof;
FIG. 2 is a front elevational view thereof;
FIG. 3 is a rear elevational view thereof;
FIG. 4 is a top view thereof;
FIG. 5 is a bottom view thereof;
FIG. 6 is a right side elevational view thereof; and,
FIG. 7 is a left side elevational view thereof.
